UNITED STATES PATENT OFFICE

LOUIS H. MORIN, OF NEW YORK, N. Y.

DIALING DEVICE

Application filed January 15, 1932. Serial No. 586,903.

In my copending application Serial No. 586,901, filed Jan. 15, 1932, for Dialing device, and Serial No. 586,902, filed Jan. 15, 1932, for Dialing device, I have illustrated and described devices for automatically actuating the dial of an automatic telephone with which devices the dial of a telephone may be selectively and progressively actuated to dial the items of a telephone call number. These devices include power receiving mechanism to which power may be uniformly applied and dial operating mechanism which operates the dial. The power applied to the power receiving mechanism is transmitted to the dial operating mechanism for operating the dial of a telephone. Control devices, one for each call number, for which it is desired to use the dialing device, translate the motion uniformly imparted to the power receiving mechanism into selective movements of the dial operating mechanism. In one of these devices, the control element acts as a motion transmitting link between the power receiving mechanism and the dial actuating mechanism, and transmits more or less of the movement imparted to the power receiving mechanism to the dial operating mechanism depending upon the items in the call number which the control element represents. In certain respects this dialing device was limited to call numbers having a definite number of items.

In the other device above referred to, the control element acts to restrict movement of the dial operating means to selectively limit movement of the telephone dial. The control elements of this dialing device and the dialing device are flexible in that telephone numbers having varying numbers of items may be dialed with the device. In addition, since the control element is used as a limiting device, it can be made of much lighter material than the control elements which act as a link in the transmission of motion from one part of the mechanism to the other. Both of these devices avoid the necessity of the operator knowing the characters of the language in which the telephone call numbers are expressed, the necessity of translating a call number into the characters printed on the face of the dial and the possibility of mak-

ing mistakes by the closeness of the openings to one another on the ordinary telephone dial.

By my present invention, I am enabled to construct a dialing device of this type which is simple in construction, comparatively inexpensive to manufacture and with which a translating element that is more compact may be used.

In accordance with my present invention, I utilize the translating element as a limiting member to limit the operation of the dial actuating means. The translating element may, however, in this form of my invention, be rectangular having one edge thereof with a plurality of abutment surfaces formed thereon, which abutment surfaces act to selectively limit the movement of the operating means. This translating element is shiftable transversely of the operating means to bring the several abutment surfaces in sequence into operative relation with the dial operating means. The dialing device, when it is desired to actuate the dial in the ordinary way, may be entirely removed from the telephone or switchboard as the case may be. With the dialing device is provided an adapter which positions the dialing device, when placed over the dial, so that the dial operating means thereof properly engages the dial to operate the same.

Specifically, the dialing device of my present invention includes a dial operating member in the form of a shaft. To one end of this shaft, there is secured a manual operating lever through which the shaft, which is rotatably mounted in a frame, may be rotated. The other end of the shaft is connectable to the dial of an automatic telephone. This connection is effected through a radial arm that is secured to the shaft and has a projection thereon that extends into the last opening in the dial. It will be apparent that as the dial operating member is rotated through the manually actuated lever, the dial of the telephone will be rotated. In conjunction with this dial operating member there is provided a spiral cam and a slideable member having a cam follower which engages the cam. A spring holds the cam follower of the slide in contact with the cam

and when the operating member is rotated the slide is reciprocated. On the slide, there is an abutment and between this abutment and the cam, a control member is placed so that when the slide is operated the abutment engages an abutment surface on the control member and the slide becomes wedged between the abutment surface on the control member and the cam, thus preventing further movement of the operating member. The control element is substantially rectangular and has a plurality of abutment surfaces on one edge thereof, the number of which correspond to the number of items in the telephone call number to be dialed. These abutment surfaces are so formed that they limit the movement of the slide and consequently the movement of the operating member to a particular predetermined amount. For any given abutment surface, therefore, the dial operating member can only be rotated to such an extent as to dial a particular item. Co-operating with the dial operating member there is a pawl which engages ratchet teeth formed on the edge of the translating element opposite to the edge having the abutment surfaces and this pawl serves to shift the translating element, transversely of the operating member and the slide each time the operating member is actuated. In this way, successive abutment surfaces of the translating element are brought into the path of the abutment on the slide and continued actuation of the dial operating member is selectively limited so that a telephone call number is progressively dialed.

My present invention will be more clearly understood from the following particular description of one embodiment thereof which is shown in the accompanying drawing in which:

Fig. 1 is a fragmentary elevation of a telephone base having the dialing device positioned thereon, the dialing device being in section;

Fig. 2 is a sectional plan of the dialing device taken on the line 2—2 of Fig. 1;

Fig. 3 is also a sectional plan taken on the line 3—3 of Fig. 1;

Fig. 4 is a fragmentary sectional plan, taken on the line 4—4 of Fig. 1;

Fig. 5 is a perspective of a control element used with the dialing device; and

Fig. 6 is a fragmentary plan of a control element illustrating the relation of the control surfaces to the call number items.

In the drawing, the dialing device is illustrated as it is applied to a telephone stand 1 having a manually actuated dial 2. For this purpose, there is provided what may be conveniently termed an adapter. This adapter consists of a cylindrical frame 3 having an inwardly extending flange 4 at one end and an outwardly flaring flange 5 at the opposite end. The outwardly flaring flange is shaped

to exactly fit the contour of the telephone about the dial, or the base of the dial where the dial is located on a switchboard. Along the side of this base member, there is formed an internal, longitudinal groove 6 which is provided to receive the stop 7 associated with the telephone dial. By means of this groove, and the stop for the telephone dial, the adapter can only be placed over the dial in one position and when so placed is prevented from moving about the dial. To the inwardly extending flange 4 of the adapter is secured the casing or frame of the dial operating device.

The casing or frame of the dial operating device comprises three sections, a base section 8, a cover section 9 and an intermediate section 10. The casing is divided into three sections to facilitate manufacture and assembly of the dialing mechanism. The base section consists of a metal plate and is secured to the inwardly extending flange 4 of the adapter through lugs 8a and to the other sections of the frame. In plan, this section of the frame has a substantially circular portion and a rectangular portion extending radially from the circular portion. The circular portion has a circular recess 11 formed therein which is concentric with an opening 12 that passes through the member. This opening through the member is provided for a shaft or operating member 13 which extends through and is journaled in the base member of the frame. When the dialing device is positioned over the telephone dial, the shaft 13 is coaxial with the dial. The end of the shaft extending through the base member is squared and has secured thereon a radial arm 14. The radial arm secured to the end of the shaft is off-set so that the outer end thereof lies in close proximity to the plane of the dial adjacent that portion of the dial having the finger openings therethrough. On this outer end of the radial arm there is secured a roller 15 which extends into the last opening in the dial. On the shaft, adjacent the end that extends through the base of the casing, there is formed a cam 16 having a spiral cam surface. This cam fits within the circular recess 11 in the bottom of the casing.

Radially of the circular recess in the bottom member, there is formed in the rectangular section of the bottom of the casing a groove 17 the sides of which form a guide for a slide 18. The slide has a slot 19 therethrough through which the shaft passes and the slide is reciprocally mounted to move perpendicular to the shaft. On one end of this slide, there is secured a depending projection 20 of rectangular configuration that fits into the aforementioned groove 17. This projection engages the sides of the groove and guides the slide in its reciprocating movements. A compression spring 21 within the groove acts between one side of this guide

projection and the end of the groove and resiliently urges the projection toward the radially outward end of the groove. On the opposite end of the slide, there is secured a 5 depending cam follower 22 that is rotatably mounted upon a pin 23 extending through the slide. A groove 24 is formed in the bottom of the circular recess to receive the end of the pin on which this cam follower is 10 mounted, the groove extending a little beyond the circumference of the circular cam recess. The spring 21 acting upon the guide projection tends to maintain the cam follower 22 in contact with the spiral cam surface. It will be apparent that when the 15 shaft 13 is rotated the spiral cam acting upon the cam follower will cause the slide to move perpendicular to the shaft. For the purpose of rotating the shaft, a lever 25 is mounted 20 on the upper end of the shaft and secured thereto by means of a machine screw 26. The shaft above the cam thereon is squared and the end of the shaft passes into a squared recess through the lever. On the outer end 25 of the lever there is provided a handle 27 for manually manipulating the operating member.

Above the slide of the dialing device is the 30 intermediate section of the casing. The lower surface of this section contacts with the upper surface of the slide and holds the slide in place, longitudinally of the shaft, with respect to the cam on the shaft. This intermediate portion is provided with a slot 35 28 through which an abutment 29 on the slide extends and in which the abutment moves. This section also has an opening therethrough concentric with the shaft 13 and substantially 40 of the same diameter as the cam recess in the base member. Through this opening, the shaft extends, and on the shaft at this point is fitted a bushing 30. The bushing is provided with a squared opening through the center thereof which receives the squared shaft so 45 that the bushing is rotatable with the shaft. The bushing has a pair of concentric, parallel, circumferential flanges 31 formed thereon between which there is secured a pawl 32. This pawl is secured between the flanges by 50 a pin 33 which extends through the flanges and the pawl so that the pawl is pivotally mounted about the pin. A second pin 34 secures one end of a leaf spring 35 that passes around the bushing, between the flanges, and 55 engages the pawl. Substantially tangent to the opening through this section of the casing, there is a rectangular groove 36 which passes from one side of the member to the other. This groove communicates with the 60 circular opening through a slot 37 through which the end of the pawl is adapted to extend when the operating member approaches, and is in the inoperative position. An inclined face 38 on the pawl engages one edge 65 of the slot when the operating member is in

the inoperative position. To one side of this slot through which the pawl extends, there is formed a recess in which a second pawl 39 is mounted. This second pawl is resiliently urged by a spring 40 towards the rectangular transverse groove 36 with which the recess in which the pawl is mounted communicates. The recess is so formed that there is a projection having an abutment surface 41 that engages an abutment surface formed on the pawl to limit its movement in response to the action of the spring. 70

Over the intermediate section of the casing fits the cover section which consists of a plate having a hub 42 formed thereon concentric with the shaft. This hub has a recess therein concentric with the opening through the intermediate section and the recess in the bottom section. This recess together with the opening through the intermediate section 80 forms a house for the aforementioned bushing 30 with the circumferential flanges. An opening is formed through the center of the hub through which the upper end of the shaft extends and in which the upper portion of the bushing 30 is journaled. Between the top of the hub and the flange, there is wound about the bushing a spring 43 which is secured at one end in the hub and at the other end to the pin which secures the pawl to the flanges. 90 This spring acts to return the operating member to its initial position when it has been operated to actuate the telephone dial. 95

With this dialing device a translating or control element 44 is used to limit successive movements of the dial operating member in response to manual actuation through the hand lever. This translating element consists of a substantially rectangular piece of metal or any stiff fiber material and somewhat resembles a key. This piece of metal has a plurality of slots cut in one edge thereof, one for each item in a telephone call number which this element represents. The base of these slots and the edges of the projections formed by cutting the slots form abutment surfaces 45 to selectively limit movement of the dial operating member. The depth of a particular slot will determine the item to which the dialing device will actuate a telephone dial when that particular slot is in alignment with the abutment 29 on the slide 18. The opposite edge of the key has a plurality of ratchet teeth 46 thereon which are adapted to cooperate with the two pawls 32 105 and 39. 110

The key is inserted in the dialing device between the cover section of the casing and the intermediate section in the transverse rectangular slot 36. It is pushed into this 115 slot until it is restrained by the pawls 32 and 39. The forward edge of the first tooth on the translating element will engage the rear surface of the pawl 32 secured to the operating member and further movement of the 120 130

translating element inwardly will be restrained because of the abutment of this pawl against the edge of the slot in which the pawl operates. The pawl 39 will engage a tooth 5 on the translating element and will prevent the element from being withdrawn. When the first tooth in the translating element engages the pawl 32 on the operating member the translating element is positioned with 10 the first slot or abutment surface 45 thereof in the path of the abutment on the slide. As the operating member is rotated to actuate the dial, the pawl 32 thereof will be withdrawn, by virtue of the inclined face on the 15 first tooth of the translating element and the edge of the slot 37, into the circular opening in the intermediate section of the casing. The cam 16 acting upon the cam follower 22 secured to the slide 18 will cause the slide 20 to move perpendicular to the operating member until the abutment 29 on the slide engages the base or abutment surface of the first slot in the translating element. It will be noted that the translating element is so 25 positioned that the slide becomes wedged between the cam and the abutment surface of the translating element so that further movement of the operating member is completely restrained. The dial operating member 30 is then released and on the return movement the pawl extends through the slot and engages the rear edge of the first tooth on the translating device and shifts the translating device transversely of the operating member 35 an amount equivalent to one abutment surface 45 so that the second abutment surface of the translating element is brought into the path of the abutment on the slide. This operation is repeated for each item in 40 the telephone call number, the pawl 39 preventing reverse movement of the translating element during its progress through the dialing device. At the end of the dialing of a telephone call number the end of the last 45 abutment surface 45a on the translating element engages the abutment and this is such that movement of the operating member is totally restrained and further actuation of the dial is prevented.

50 It will of course be obvious that there need be one abutment surface for each item in the telephone call number plus a stop surface for preventing further actuation of the telephone dial when the number has been dialed.

55 It will also be obvious that the depth of a slot cut to form an abutment surface in the translating element will determine the item to which a dial is actuated when that particular abutment surface is in the path of the 60 abutment on the slide. The relation of the abutment surfaces to the items of telephone call number or the characters printed on a dial is illustrated in Figure 6.

65 The device can be used with translating elements having any number of abutment

surfaces, that is, the dialing device is universal in its application in that it can be used for dialing telephone call numbers irrespective of the number of items in the call number. The translating device illustrated has abutment surfaces formed thereon which correspond to the telephone number Wo-2-50919. When it is desired to call a number the key in the dialing device is removed and another inserted. The insertion of a key 75 in the dialing device will force a key that has been previously used out through the opposite end of the slot.

If it is desired to use the telephone dial in the ordinary way the dialing device may be removed from the telephone simply by lifting it off. In replacing the dialing device, the spring 43 acting on the operating member maintains that member in a position such that the roller on the radial arm 80 will enter the last slot in the dialing device, the dialing device being secured to the adapter, it is positioned in the same manner each time that it is applied to the telephone.

It will be obvious that various changes 85 may be made in the details of the embodiment illustrated above and particularly described within the scope of my invention as expressed in the appended claims.

I claim:

1. A telephone dialing device for selectively actuating the dial of an automatic telephone comprising dial operating means connectable to the dial of a telephone, and translating means including a series of controls shiftable upon each actuation of the dial transversely of the operating means into position to selectively control movements of the operating member.

2. A telephone dialing device for selectively actuating the dial of an automatic telephone comprising dial operating means connectable to the dial of a telephone, and a translating element having a series of limiting surfaces thereon shiftable upon each actuation of the dial transversely of the dial operating means for bringing the several limiting surfaces into operative relation to the operating means to selectively limit successive movements of the operating member.

3. A telephone dialing device for selectively actuating the dial of an automatic telephone comprising a dial operating member connectable to the dial of an automatic telephone and adapted to actuate the dial, and a translating element having a series of limiting surfaces thereon shiftable transversely of the operating member for bringing the several limiting surfaces into operative relation to the operating member to selectively limit successive movements thereof.

4. A telephone dialing device for selectively actuating the dial of an automatic

telephone comprising a dial operating member connectable to the dial of an automatic telephone, an abutment operatively related to said operating member and movable transversely thereof, and a translating element having a series of abutment surfaces shiftable transversely of the operating member for bringing the several abutment surfaces into the path of the abutment associated with the operating member to selectively limit successive movements thereof.

5. A telephone dialing device for selectively actuating the dial of an automatic telephone comprising a dial operating member connectable to the dial of an automatic telephone, a slidably mounted member operatively related to the operating member and movable therewith, an abutment carried by said slidably member, a translating element having a series of abutment surfaces each adapted to engage the abutment on said slidably member, and means for shifting the translating element to bring the abutment surfaces thereof in sequence into the path of the abutment on the slidably member.

6. A telephone dialing device for selectively actuating the dial of an automatic telephone comprising a rotatably mounted dial operating member connectable to the dial of an automatic telephone, means for rotating the dial operating member, a cam on the dial operating member, a slidably mounted member, a cam follower on the slidably mounted member engaging the cam on the operating member, an abutment carried by the slidably member, and an abutment surface in the path of the abutment on said slidably member and adapted to cooperate therewith to limit the movement of the operating member.

7. A telephone dialing device for selectively actuating the dial of an automatic telephone comprising a rotatably mounted dial operating member connectable to the dial of an automatic telephone, a cam on the operating member, means for rotating the operating member to actuate the dial, a slidably mounted member, a cam follower carried by the slidably member and engaging the cam on the operating member, an abutment on the slidably member, and an abutment surface between the cam and the abutment on the slidably member for selectively limiting the movement of the operating member.

55. 8. A telephone dialing device for selectively actuating the dial of an automatic telephone comprising a rotatably mounted dial

operating member connectable to the dial of an automatic telephone, a spiral cam on the operating member, means for rotating the operating member to actuate the dial, a slidably mounted member slidably transversely of the operating member, a cam follower on the slidably mounted member and engaging the cam on the operating member, an abutment on the slidably mounted member, and an abutment surface between the abutment and the cam follower for engaging the abutment to limit movement of the operating member.

9. A telephone dialing device for actuating the dial of an automatic telephone comprising a dial operating means, a translating element having a series of controlling surfaces thereon for selectively limiting movement of the dial operating means, a series of ratchet teeth on said translating element, and a pawl actuated by said operating means for shifting the translating element transversely thereof.

10. A telephone dialing device for actuating the dial of an automatic telephone comprising dial operating means, a rectangular translating element having controlling surfaces on one edge thereof for selectively limiting movement of the dial operating means, and ratchet teeth on the opposite edge thereof, a pawl associated with the dial operating means and adapted to engage the ratchet teeth on the translating element to shift the same in one direction, a second pawl engaging the ratchet teeth for preventing movement of the translating element, the two pawls acting to position the translating element on insertion in the dialing device.

11. A translating element for a telephone dialing device comprising a rectangular member, a series of limiting surfaces formed along one edge thereof, each surface representing a particular item in a telephone call number, and means along the opposite edge for shifting the translating element.

12. A translating element for a telephone dialing device comprising a rectangular member, a series of limiting surfaces formed along one edge thereof, each surface representing a particular item in a telephone call number, and ratchet teeth formed along the opposite edge thereof for shifting the translating element.

In witness whereof, I hereunto subscribe my signature.

LOUIS H. MORIN.
